CASE FOR AN ELECTRIC METER

George D. Perkins and David E. Workman, both of Pasadena, Calif., assignors to Pendleton Tool Industries, Inc., Los Angeles, Calif., a corporation of Delaware

Filed Sept. 14, 1965, Ser. No. 86,988

Term of patent 14 years

(Cl. D26—1)

FIG. 1 is a perspective view of a case for an electric meter embodying our new design;

FIG. 2 is a side elevational view thereof;

FIG. 3 is a front elevational view thereof; and

FIG. 4 is a top plan view thereof.

The essential features of our design are shown in full lines.

We claim:

The ornamental design for a case for an electric meter, substantially as shown and described.
